DISPLAY CABINET

Richard R. Volz, Ridgewood, N. J., assignor, by mesne assignments, to Coats & Clark Inc., Wilmington, Del., a corporation of Delaware

Application October 28, 1952, Serial No. 317,269

4 Claims. (Cl. 211—130)

This invention relates to a display cabinet or stand for cylindrically-shaped articles such as thread spools, zippers packaged in coiled form, and like articles and particularly to a device which enables the purchaser to serve himself. A principal object is to provide a display device of the self-service type which will keep the articles substantially free of dust and other atmospheric contaminants which up to now, at least, and particularly in the case of thread spools, have been the cause of a serious problem of thread soilage. Few purchasers care to buy soiled thread or soiled articles in general. Unlike prior devices, the present cabinet avoids the exposure of excessive quantities of articles which, especially if the turnover is slow, only aggravates the soiling problem. Among other advantages the invention enables convenient servicing of the display cabinet to be made, permits the brand of the goods to be prominently identified on the cabinet, facilitates shipping of the device by virtue of a collapsible construction, and provides a cabinet of enhanced attractiveness.

The invention may be better understood by consulting the accompanying drawings in which a preferred embodiment is illustrated and in which

Fig. 1 is a front elevational view of the cabinet in its extended or non-collapsed position;

Figs. 2 and 3 are end elevational views of the cabinet in its extended and collapsed positions, respectively, Fig. 3 being partly broken away and partly sectioned;

Fig. 4 is a plan view of the cabinet in extended form;

Fig. 5 is a back elevational view of the cabinet in extended form, part of the construction being omitted;

Fig. 6 is an enlarged partial view showing in perspective a detail of the cabinet base construction;

Fig. 7 is an enlarged view taken along the line VII—VII of Fig. 4;

Fig. 8 is an enlarged, partial view of the right hand side of the back of the cabinet; more particularly it is a view looking along the line VIII—VIII of Fig. 4, part of the construction being omitted;

Fig. 9 is an enlarged view taken along the line IX—IX of Fig. 4;

Fig. 10 is an enlarged, fragmental view, in perspective, looking along the line X—X in Fig. 4;

Fig. 11 is an enlarged view taken along line XI—XI of Fig. 3;

Fig. 12 is an enlarged view, partly broken away and in section, showing details of a modified construction;

Fig. 13 is a view like Fig. 8 but showing a modification of Fig. 12;

Fig. 14 is an enlarged, fragmental, sectional view showing a modification of Fig. 12;

Fig. 15 is an enlarged sectional view along the line XV—XV of Fig. 12;

Fig. 16 is a fragmental view along the line XVI—XVI of Fig. 15;

Fig. 17 is a broken view, partly in section, looking in the direction of the arrow A in Fig. 14;

Fig. 18 is a view along the line XVIII—XVIII of Fig. 17; and

2

Fig. 19 is an enlarged fragmental view looking in the direction of the arrow B in Fig. 12.

The views of Figs. 1 to 11 will be described in connection with the display of thread spools, some of which are apparent in the drawings. It will be understood that other articles may be similarly displayed. As may be seen in Fig. 3, the display cabinet comprises a stack of trays 10, 11, 12, 13, and 14, one tray being superimposed upon another as shown. Means in the form of levers are provided for enabling all the trays above the bottom one to swing backwardly to an offset or extended position, as in Fig. 2, in which the trays are upwardly inclined from front to back, presenting a stepped arrangement with each tray overlapping the rearward portion, say at least half thereof, of the tray immediately beneath it. As shown, the levers are disposed at the ends of the trays and pivotally connect all the trays together. Lever 15 connects ends 10a, 11a, and 12a of trays 10, 11, and 12, respectively; lever 16 connects ends 10a to 14a of trays 10 to 14, respectively; and lever 17 connects ends 12a to 14a of trays 12 to 14, respectively. On the opposite ends of the cabinet a similar arrangement of levers is provided.

These levers also enable the trays to swing forwardly from their extended position of Fig. 2 to their stacked or collapsed position of Fig. 3.

In this connection, and referring to Figs. 1 and 2, that dimension of the cabinet which extends from the front A to the back B is usually called the depth; the dimension from B to top C is the height; and the dimension from end D to end E is the width.

Trays 11, 12, and 13 are identical. Trays 10 and 14, while substantially the same as 11, 12, and 13, contain added features. The following description of tray 11 will apply to all the trays. It comprises a pair of opposite end walls 11a, 11b, to which levers 15, 16 and 15a, 16a, respectively, are connected by pivots 18, 19 and 18a, 19a. The upper edges of end walls 11a and 11b terminate in inwardly disposed ledges 11c, 11d (Fig. 4), which ledges support tray 12 immediately above the tray 11. Tray 11 has a floor 11e (Fig. 7) extending between the end walls on which a plurality of spool-supporting runways 11f are formed by the partitions 11g. The runways 11f are disposed transversely across the tray from end to end, with each runway extending from the front to the back of the tray. As may be seen in Fig. 2, the spools are positioned on the runways in side to side relation. Floor 11e is stepped upwardly at each end of the tray, as shown at 11h so that the end portion 11i of the floor parallels and makes contact with the end wall 11b. Tray 11 also has a front wall 11j (Figs. 1 and 9) extending transversely across the tray having a series of cut-outs 11k in the upper edge of the same, each cut-out being aligned with a runway and serving to expose the spools in the runway. The wall 11j extends a short distance below the floor of the tray and then terminates in a reversely bent portion, as seen at 11m (Fig. 9). Along its rear ends, tray 11 has a forwardly inclined, grooved, multi-slotted member 11n. Each slot 11o (Fig. 5) of this member is aligned with a runway. A spool-identifying strip 20 (note tray 14 in Fig. 8) is insertable in the groove of member 11n, having thereon a series of spaced legends which are exposable to view through the slots 11o and which serve to identify the spools in each runway.

Tray 11 has an open top 21 (Fig. 9) through which the thread spools are visible and accessible, and it also has an open back side 22 through which fresh spools may conveniently be added to the runways by a sales clerk. The spools simply roll downwardly in the runways from back to front under the influence of gravity.

The construction of identical trays 11, 12, and 13 is further illustrated by Fig. 10, in which a fragmental, perspective view of tray 12 is shown, and in which may be

seen end wall 12b, the upper edge of which terminates in the ledge 12d. A portion of floor 12e is visible on which the runways 12f are formed by partition 12g. Floor 12e is stepped upwardly at 12h, and the end portion 12i parallels and touches wall 12b. Wall 12j extends across the front of the tray, being provided with cut-outs 12k and the downwardly extending reversely bent portion 12m. Tray 12 is supported on the ledge 11d of wall 11b of tray 11 immediately below and also by being secured, as by spot welding, to the wall 12b.

Bottom tray 10 differs from the other trays by having end walls 10a and 10b which are of different shape and somewhat higher than the end walls of the other trays. Walls 10a and 10b rest on a supporting base 30 (Figs. 6 and 7) and slope upwardly from the front to the back of the tray. As in the case of the other trays, the floor 10e of tray 10 is inclined (Fig. 2) to the horizontal, and it is supported in this position by securing the end portions 10i of the floor to the end walls of the tray. At its back end, floor 10e rests on a ledge 10p of a back wall 10q (Fig. 2) which extends between end walls 10a and 10b below the slotted member 10n. In other respects the tray 10 is like tray 11.

End walls 10a and 10b of tray 10 are supported on base 30 by a cross member 31 (Fig. 6). Between each end wall and base 30 there is provided an L-shaped groove, one of which is shown at 32 as being formed by attaching an L-shaped plate 33 to the end wall 10a and base 30.

Tray 14, which is the top tray of the cabinet, differs from tray 11 by having a panel 34 covering the rearward half of the tray and also by having a second panel 35 extending upwardly from the rear of the tray. These panels 34 and 35 are adapted to receive advertising, trademark, or other indicia. Panel 35 has a pair of handles 36, 37 on its back side to enable the trays to be moved from their stacked to their extended position and vice versa. Intermediate the handles is a clip 38 for holding cards, signs, and the like. Panel 34 is supported at its ends on the ledges 14c and 14d of end walls 14a and 14b of tray 14, and intermediate its ends is supported by the member or strip 39, which in turn rests on the floor of tray 14. Panel 34 also has a depending section 40.

As shown in Figs. 2 and 3, the cabinet is equipped with a pair of opposite, rearwardly extending, end panels 41, 42 for supporting the cabinet when the trays are in their extended position. These panels are alike so that a description of one of them will suffice. Considering panel 42, it has on its lower edge a forwardly extending L-shaped member 43 engageable with the L-shaped groove 32 above referred to. At the back end 44 of member 43 is an L-shaped bracket 45 attached to panel 42, which, when member 43 is fully engaged in groove 32, engages the back wall 10q of tray 10 (Figs. 3 and 8). A screw 46 may be employed to hold bracket 45 in engagement with wall 10q. Panel 42 has a stepped upper edge on which steps 47, 48, 49 and 50 are provided, these steps increasing in height from the front to the back of the panel. The steps of panel 42 correspond to those of panel 41 and form pairs of steps, each pair serving to support a tray of the cabinet when the trays are extended. The steps of panel 42 have inwardly disposed ledges 47a to 50a, respectively, which with the corresponding ledges of panel 41 serve to support trays 11 to 14, respectively. On ledge 50a of panel 42 is a lug 51 which, when the trays are extended, engages a corresponding recess 52 (Fig. 2) in the floor of tray 14. Panel 41 has a similar construction.

Panels 41, 42 are connected and braced by a detachable cross piece 53 (Figs. 3, 4, and 11) which is of rectangular shape and has the edges thereof bent forwardly, as at 54, 55, and 56. The end edge opposite 54 is not shown but is also bent forwardly. Means are provided for attaching the end edges of the cross piece to

the panels 41, 42, and comprises, in the case of edge 54, a strip 57 secured to the inner side of panel 42 as by spot welding, a spacer strip 58 being inserted to provide a slot 59. A yieldable strip 60 is secured to panel 42 at 61, this strip serving to retain the cross piece 53 in position. By depressing the spring-like part 62 until it engages panel 42, the cross piece may be moved rearwardly out of slot 59. Screw or pin 63 in edge 55 may engage an opening in the bottom ledge 64 of panel 42 to further support the cross piece between the panels. Panel 42 is further formed with an inwardly disposed ledge 65.

The cabinet is supported on rubber discs 66, the shafts 67 of which engage spring retainers 68 (Fig. 6) secured to the cabinet.

Each runway in a tray is adapted to hold about a dozen spools, which is a conveniently small quantity and is, in fact, the number usually packed in a box of spools. Thus, no excessive amounts of any one particular spool item can accumulate in the cabinet and be exposed to atmospheric contamination or changes for very long periods. As will be apparent, the trays may be constructed to hold a greater or lesser number than twelve spools per runway.

During business hours, the cabinet is maintained in its extended position, and customers may inspect the thread displayed on it and serve themselves. At the close of the day, the clerk collapses the cabinet by grasping the handles and moving them forwardly until the trays are in the position shown in Fig. 3. During the latter movement, the handles are lifted somewhat as they are moved forwardly. With the trays stacked, as in Fig. 3, the spools on one tray will be covered by the tray immediately above it, and thus all the spools will be protected against dust and other atmospheric contaminants except those in the forward part of the top tray and these, of course, may be covered in any appropriate way as by placing a sheet or cloth over them. Boxed spools for replenishing the supply in the cabinet may be stacked in the back part of the cabinet, that is, back of the cross piece 53 and underneath the extended trays. In order to replenish the cabinet, the clerk simply adds spools to the back end of each runway and the spools will roll forwardly down the runways by gravity. Legends on the strips 20 insure that the correct spools are placed in the correct runways. As will be understood, the trays are preferably in their stacked position during replenishing.

A modified tray construction is shown in Figs. 12 to 19 and is particularly characterized by having article restraining means at the back side of the tray which, while permitting the loading of the runways of the tray with cylindrical articles, serves to prevent the articles from being ejected through the back side as might happen when a sales person attempts to load the runways beyond their capacity from the front side. Such restraining means comprise a swingable member or barrier in the form of a flat strip 70 which extends transversely across the back side of each tray. As all of these swingable members are the same, only that on tray 14 will be described in detail. Intermediate its end portions and throughout most of its length the member 70 is of double thickness (Figs. 17 and 18). The member may conveniently be formed from a flat, appropriately shaped piece of sheet metal by turning up the bevelled ears 71a and 71b and reversely folding a pair of panels 70a and 70b into the position shown in Figs. 17 and 18. Ears 71a and 71b serve as mounting portions for pivotally connecting the member to the opposite end walls 14a and 14b (Fig. 12). The pivotal connection is provided by mounting each ear on a short axle 72 (Fig. 15) which is shown as a tubular piece having an outer head 73 and a flanged inner end 74. The ears 71a and 71b have openings 75a and 75b, respectively, for receiving the axles, the inner ends of the latter then being flanged as shown to retain the member 70 in position.

When not engaged by an article, member 70 depends from its supporting axles, as in tray 12 shown in Fig. 14, and is freely swingable. Cylindrically shaped articles, which may be thread spools or, as is intended to be indicated in Figs. 12-19, zippers wound into a concentrically coiled or rolled form and placed in a cylindrically shaped transparent container, one zipper per container, are fed to the runways of the tray from the back side, as shown in trays 14 and 13 in Fig. 14. The articles are pushed against the swingable member 70, which moves inwardly easily to permit the article to enter the runway and roll downwardly to the front portion thereof. The articles, which are somewhat larger than the thread spools shown in Figs. 1-11, fill a runway in the manner shown in Fig. 12, the rear article engaging the underside of member 70. In case a sales person attempts to load a runway beyond its capacity, or if the cabinet is accidentally tilted backwards, the articles will not be displaced from or fall through the back side of any tray because the member 70, which is engaged by the rear article, may not from such engaged position be swung outwardly of the back side of the tray. This is because the rear article makes contact with member 70 at a point too close to the pivot point of the member to effect a swinging action on the member. In other words, the torque which the engaging article shown in Fig. 12 can exert on the member 70 is not sufficient to turn the member, considering the latter as a lever.

As will be appreciated, the restraining action of member 70 on articles in the tray will prevail when a runway is filled to capacity so that the rear article engages member 70, as described. When no runways are filled, the restraining action may still take place, as when the cabinet is tilted backwards and articles roll back and engage the member.

In Figs. 12 and 19, the front wall of each tray is provided with a slotted or grooved member for receiving an article-identifying strip 80, note Fig. 12. This slotted member comprises a narrow elongated piece 76 having a back wall 77 and inwardly folded longitudinal edges 78 by means of which a slot or groove 79 is provided for the strip 80.

As shown in Figs. 12 and 14, the vertical panel, designated 35a, on the top tray 14 may be inclined slightly to the rear and may be connected to a pair of tapered side panels 35b and 35c.

It will be appreciated that the size of the cabinet, trays, and runways, the number of trays, and the number of runways per tray are variable and will suit the type of article to be displayed. Irrespective of the articles displayed, the cabinet enables a full color range of articles to be on display at all times and permits the purchaser to obtain a full view of the article and its color. A sales person can tell at a glance what articles are missing and with the help of the front and/or rear identifying strips can quickly restock them from the boxed supply stored underneath the trays. When the cabinet is to be moved or shipped away, it may be dismantled quite easily by collapsing the trays and removing the cross piece and panels.

This application is a continuation-in-part of co-pending application Serial Number 240,390, filed August 4, 1951, now abandoned.

Although the invention has been described in connection with a specific embodiment, it should be understood that it is capable of obvious variations.

In the light of the foregoing, the following is claimed:

1. A self-service display cabinet for cylindrically-shaped articles comprising a stack of trays of uniform length and width, one tray being superimposed upon another; means for enabling all the trays above the bottom one to swing backwardly to an offset extended position in which the trays are upwardly inclined from front to back and present a stepped arrangement, each tray overlapping at least the rearward half of the tray immediately

beneath it, said means also enabling the trays to swing forwardly from their extended position to a stacked or collapsed position; each tray having an open top through which the articles are visible and accessible and also having an open back side through which fresh articles may be added, the articles being movable downwardly in the trays by means of gravity; a pair of rearwardly extending end panels for supporting the cabinet when said trays are in their extended position, each end panel having a stepped upper edge with the steps increasing in height from the front to the back of the panel, the steps of one end panel corresponding to those of the other to form pairs of steps, each pair of steps being adapted to support thereon a tray of the cabinet when the trays are extended.

2. A self-service display cabinet for cylindrically-shaped articles comprising a stack of rectangularly shaped trays of uniform length and width, one tray being superimposed upon another; means for enabling all the trays above the bottom one to swing backwardly to an offset extended position in which the trays are inclined and present a stepped arrangement, each tray overlapping at least the rearward half of the top side of the tray immediately beneath it, said means also enabling the trays to swing forwardly from their extended position to a stacked or collapsed position; said bottom tray having end walls which slope upwardly from front to back, a groove on the inner side of each said bottom tray end wall, a pair of rearwardly extending end panels for supporting the cabinet when said trays are in their extended position, each end panel having a forwardly extending member engageable with a groove on the bottom tray end wall, each end panel having a stepped upper edge with the steps increasing in height from the front to the back of the panel, the steps of one end panel corresponding to those of the other to form pairs of steps, each pair of steps being adapted to support thereon a tray of the cabinet when the trays are extended; said cabinet, when the trays are collapsed, serving to protect the articles from being soiled by dust and the like, and providing, when the trays are extended, a maximum display of the articles.

3. A self-service article display cabinet comprising a stack of trays, one tray being superimposed upon another; means on the stacked trays for enabling the trays above the bottom one to swing backwardly to an offset extended position in which the stack of trays is upwardly inclined from front to back and presents a stepped arrangement, each tray of the inclined stack overlapping at least the rearward half of the tray immediately beneath it; a grooved, elongated piece extending along the front side of each tray for receiving a strip having article-identifying legends thereon, a forwardly inclined, grooved, multi-slotted member extending along the back side of each tray for receiving a strip having article-identifying legends thereon which are exposable through said slots; each tray having an open top through which the articles are visible and accessible and also having a back side through which articles may be added, the articles being movable downwardly in the trays by means of gravity; the top tray of said cabinet having a first panel covering the rear portion of the tray and also having a second panel extending upwardly from the rear of the tray, said first and second panels being adapted to receive advertising or other indicia; a pair of rearwardly extending end panels for supporting the cabinet when said trays are in their extended position, each end panel having a forwardly extending member engageable with the bottom tray, each end panel having a stepped upper side and each tray being adapted to rest on a pair of corresponding steps of said panels, a cross member connecting said panels together and serving to support the same, said cabinet having a space between said end panels and underneath said extended trays for storing packaged articles; said cabinet, when the trays are collapsed, serving to protect the articles from being soiled by dust and the like, and pro-

70
75

viding, when the trays are extended, a maximum display of the articles.

4. An article display cabinet comprising a stack of trays, one tray being superimposed upon another; means on the stacked trays for enabling the trays above the bottom one to swing backwardly to an offset extended position in which the stack of trays is upwardly inclined from front to back and presents a stepped arrangement, each tray overlapping at least the rearward half of the tray immediately beneath it; a pair of rearwardly extending end panels for supporting the cabinet when said trays are in their extended position, each end panel having a forwardly extending member engageable with the bottom tray, each end panel having a stepped upper side and each tray being adapted to rest on a pair of corresponding steps of said panels, a cross member connecting said panels together and serving to support the same, said cabinet having a space between said end panels and under-

neath said extended trays for storing packaged articles; said cabinet, when the trays are collapsed, serving to protect the articles from being soiled by dust and the like, and providing, when the trays are extended, a maximum display of the articles.
